ALKYL BENZENES

Alfred W. Francis, Woodbury, and Carleton H. Schlesman, Camden, N. J., assignors to Socony-Vacuum Oil Company, Incorporated, a corporation of New York

Application July 20, 1944, Serial No. 545,885

10 Claims. (Cl. 260—671)

1

This invention relates to the manufacture of alkyl benzenes and more particularly to the preparation of such compounds from petroleum distillates. The invention is principally concerned with benzene derivatives having an alkyl group of at least two carbon atoms as the side chain.

The large demand for alkyl derivatives of benzene, such as ethyl benzene, cumene, diethyl benzene, is well known. These compounds are useful principally as solvents and as raw materials for the synthesis of other organic compounds. Benzene ordinarily is obtained from coal tar or may be separated from petroleum by known isolation methods, but the expense of these methods warrants their use only when a sufficiently high market exists. Compounds such as ethyl benzene, cumene, and diethyl benzene do not occur in either coal tar or petroleum in substantial quantities.

Alkyl benzenes may be synthesized from the benzene obtained from coal tar or from petroleum, but this is expensive because of the difficulty of isolating the benzene from other hydrocarbons present having approximately the boiling point of benzene. To isolate the benzene from petroleum by distillation, for example, and then alkylate the benzene, would be an expensive procedure.

An object of the present invention is to manufacture and recover from the benzene of petroleum, alkyl derivatives thereof. According to the invention, the desired benzene homologues are prepared and separated from the mixture of hydrocarbons occurring with the benzene by a process of selective alkylation and distillation. This involves, as a feature of the invention, carrying out the alkylation of the benzene before it has been isolated from the hydrocarbon with which it is associated in petroleum and having substantially the same boiling point as benzene.

To carry out the invention, the petroleum is first fractionally distilled and a cut is obtained in a range approximating the boiling point of benzene but below 90° C. This fractional distillation eliminates other aromatics as toluene and also saturated hydrocarbons having boiling points quite distinct from benzene. However, the cut which is obtained contains not only benzene but saturated hydrocarbons having boiling points close to benzene. This cut is then subjected to a selective alkylation process with gaseous olefins to alkylate the benzene therein. This produces the desired alkyl benzene of higher boiling points than benzene and does not alkylate any paraffins or naphthenes that may be present. The benzene which is present in the fraction

5 which is obtained is alkylated in preference to the paraffins or naphthenes that may be present because as is well known, aromatics in general are more easily alkylated than are aliphatic or alicyclic compounds.

10 After the alkylation step the resultant product is distilled to substantially the same end point as used to prepare the fraction, so as to distill off the non-aromatic material which was not alkylated and to leave as the residual liquid the alkylated benzene. The alkyl benzene so obtained can be fractionated if desired to obtain the individual alkylation products or can be used or treated in any manner that similar compounds obtained from other sources may be employed.

15 While, as stated, the invention may be applied to any appropriate hydrocarbon mixture, the invention is concerned principally with treating petroleum distillates, and, as known, many petroleum distillates are available which contain benzene. The benzene content of the reagent may be quite low, for instance, a product containing as little as 4% benzene has given a useful alkylation. But for economical operations it is better to select a material with as high a content of benzene as possible, say 50 or 60%; however, a much lower content, as, for example, 20% in a 70°-90° C. fraction, would be excellent for use in the process.

20 The olefin reagent may be pure or may be a mixture of olefins or may contain large amounts of paraffins which are inert under the conditions of reaction. Cracking still gas is a suitable olefin reagent if a pure alkyl benzene is not desired as the final product.

25 The amount of gaseous olefin added in the alkylation process will depend upon the amount of benzene present, and upon the alkylation product desired. Thus the gaseous olefin reagent does not polymerize as long as any appreciable amount of incompletely alkylated aromatic is present. However, if more than three moles of olefin is added for each mole of benzene present, the excess olefin continues to be absorbed, but some of it may result in high boiling unsaturated polymers. Therefore, the concentration of olefins to benzene should be kept below 3 moles to 1 mole. Liquid olefins cause undesirable side reactions, so that if present, in any of the reagents, they should be eliminated first by mild acid treatment.

30 As noted, the degree of alkylation may be regulated by controlling the olefin concentration. Accordingly if a mono-alkylated product, such as cumene or ethyl benzene, is desired, the amount of olefin added must be limited to not over a

half a mole for one of benzene, since mono-alkylated benzenes are alkylated further much more readily than are the original aromatics. In such a process the mono-alkylate may be separated from the unreacted material and the latter recycled for further treating.

Processes for alkylating benzene with olefins are well known and understood in the art. The only requirement of the present operation is that conditions are used which will not result in alkylation of the less reactive paraffins and naphthenes that may be present. Because of the difference in reactivity the conditions may be regulated quite feasibly so that this latter type alkylation does not occur at all or occurs so slowly that it can be neglected.

In our operations we prefer to alkylate the benzene in the presence of an aluminum chloride catalyst. Using such a catalyst, room temperature (20°-30° C.) is a suitable reaction temperature for propylene and higher olefins, although higher temperatures are permissible, and a reaction temperature of at least 40° C. should be used for alkylating with ethylene.

A further detailed understanding of the principles of this invention may be had by reference to the appended drawing and the following detailed description thereof.

In the single figure of the drawing there is diagrammatically illustrated an assembly of apparatus adapted for the accomplishment of the process of this invention.

As illustrated, a benzene rich fraction of petroleum, such as straight-run gasoline, enters a fractionator 10 through a suitable connection 11. In this fractionator, that portion of the original fraction is selected which boils below 90° C. and preferably between 71° C. and 85° C. A selected cut is passed to an alkylator 12 through a suitable connection 13 and aluminum chloride and olefins are added to the alkylator in suitable amounts from sources of supply 14 and 15, respectively. The alkylated product passes through a connection 16 to a second fractionator 17 where all material boiling below about 90° C. is removed and the remaining material which comprises the alkylated benzene is drawn off through a connection 18 to a third fractionator 19 which separates the alkylated benzene into monoalkyl benzene, then polyalkyl benzene.

In order to illustrate the invention further the following specific examples are given:

Example I

A benzene rich fraction was obtained by fractionation (B. P. 71-85° C.) of a straight run gasoline. This cut was found by analysis to contain 21% benzene by volume. The charge was then alkylated by heating it with 1.5% of its weight of anhydrous aluminum chloride to 60° C. and stirring vigorously, while adding a moderate stream of ethylene gas until 0.25 mole of ethylene for one of benzene present had been added. The product was distilled to 90° C. endpoint. The residue had a density of 0.8778 indicating that it was wholly aromatic. On further distillation practically nothing came over below 132° C. and then 70% of it distilled between 132 and 136° C. (ethylbenzene). The residue solidified on cooling, indicating that it was mostly hexaethylbenzene, M. P. 128° C.

Example II

A charge similar to that of Example I was alkylated with propylene similarly except that no

preliminary heating was necessary. For each mole of benzene present, 0.57 mole of propylene was added during about 30 minutes. The temperature rose spontaneously to 63° C. The product was washed and distilled as before, giving practically nothing between 90° C. and 148° C. Seventy-five per cent of the remainder boiled at 148-153 (isopropylbenzene or cumene) and 22% at 200-212° C. (di-isopropylbenzenes).

10 It will be appreciated from these examples that if the original charge had been first subjected to some physical separation process to isolate the benzene from the hydrocarbons of similar boiling point, so that then the isolated benzene could be 15 alkylated, a lengthy and expensive isolation procedure would have been necessary. By taking advantage of the selective alkylation properties of benzene as compared to the saturated hydrocarbons present in the charge, a rapid and inexpensive method of manufacturing the alkyl benzenes 20 may be carried out. By first obtaining a charge which boils in a range close to benzene, other aromatics not desired to be alkylated, are initially eliminated so that they are not present to consume 25 some of the olefin utilized to carry out the alkylation.

This application is a continuation-in-part of application Serial No. 356,648, filed September 13, 1940 (now, United States Letters Patent No. 30 2,371,163, issued March 13, 1945).

What is claimed is:

1. The process of obtaining alkyl benzenes substantially free of non-aromatic hydrocarbons from a petroleum oil comprising a substantial amount of benzene and a substantial amount of non-aromatic hydrocarbons wherein the boiling points of the benzene and the non-aromatic hydrocarbons are so close together that they cannot be separated feasibly by conventional fractional distillation, which process comprises distilling the oil to prepare a fraction boiling below about 90° C., subjecting the fraction to selective alkylation with a single normally gaseous olefin in the presence of aluminum chloride so as to alkylate only the benzene, and then fractionally distilling the mixture formed by said alkylation step to produce a fraction reduced in benzene content boiling below 90° C. and a fraction boiling above 90° C. which consists of alkyl benzenes substantially 50 free of non-aromatic hydrocarbons.

2. The process of obtaining alkyl benzenes substantially free of non-aromatic hydrocarbons from a petroleum oil comprising a substantial amount of benzene and a substantial amount of non-aromatic hydrocarbons wherein the boiling points of the benzene and the non-aromatic hydrocarbons are so close together that they cannot be separated feasibly by conventional fractional distillation, which process comprises distilling the oil to prepare a fraction boiling substantially between about 71° C. and 85° C., subjecting the fraction to selective alkylation with a single normally gaseous olefin in the presence of aluminum chloride so as to alkylate only the benzene, and then fractionally distilling the mixture formed by the alkylation step to produce a fraction reduced in benzene content boiling below about 90° C. and a fraction boiling above about 90° C. which consists of alkyl benzenes substantially 65 free of non-aromatic hydrocarbons.

3. The process of obtaining alkyl benzenes substantially free of non-aromatic hydrocarbons from a petroleum oil comprising a substantial amount of benzene and a substantial amount of non-aromatic hydrocarbons wherein the boiling

points of the benzene and the non-aromatic hydrocarbons are so close together that they cannot be separated feasibly by conventional fractional distillation, which process comprises distilling the oil to prepare a fraction boiling below 90° C., subjecting the fraction to selective alkylation with a single normally gaseous olefin in the presence of aluminum chloride so as to alkylate only the benzene, the olefin being present in the molar ratio of not more than 3 to 1 with respect to the benzene, and then fractionally distilling the mixture formed by the alkylation step to produce a fraction reduced in benzene content boiling below about 90° C. and a fraction boiling above about 90° C. which consists of alkyl benzenes substantially free of non-aromatic hydrocarbons.

4. The process of obtaining alkyl benzenes substantially free of non-aromatic hydrocarbons from a petroleum oil comprising a substantial amount of benzene and a substantial amount of non-aromatic hydrocarbons wherein the boiling points of the benzene and the non-aromatic hydrocarbons are so close together that they cannot be separated feasibly by conventional fractional distillation, which process comprises distilling the oil to prepare a fraction boiling substantially between about 71° C. and 85° C., subjecting the fraction to selective alkylation with a single normally gaseous olefin at a temperature not substantially in excess of 60° C. in the presence of aluminum chloride so as to alkylate only the benzene, the olefin being present in the molar ratio of not more than 3 to 1 with respect to the benzene, and then fractionally distilling the mixture formed by the alkylation step to produce a fraction reduced in benzene content boiling below about 90° C. and a fraction boiling above about 90° C. which consists of alkyl benzenes substantially free of non-aromatic hydrocarbons.

5. The process of obtaining alkyl benzenes substantially free of non-aromatic hydrocarbons from a petroleum oil comprising a substantial amount of benzene and a substantial amount of non-aromatic hydrocarbons wherein the boiling points of the benzene and the non-aromatic hydrocarbons are so close together that they cannot be separated feasibly by conventional fractional distillation, which process comprises distilling the oil to prepare a fraction boiling between about 71° C. and 85° C., subjecting the fraction to selective alkylation with a single normally gaseous olefin in a molar ratio of not more than three mols of olefin to one mol of benzene in the presence of aluminum chloride so as to alkylate only the benzene, and then fractionally distilling the mixture formed by the alkylation step to produce a fraction reduced in benzene content boiling below about 90° C. and a fraction boiling above 90° C. which consists of alkyl benzenes substantially free of non-aromatic hydrocarbons.

6. The process of obtaining substantially pure ethyl benzene from a petroleum oil comprising a substantial amount of benzene and a substantial amount of non-aromatic hydrocarbons wherein the boiling point of the benzene and the non-aromatic hydrocarbons are so close together that they cannot be separated feasibly by a conventional fractional distillation, which process comprises distilling the oils to prepare a fraction boiling below about 90° C. subjecting the fraction to selective ethylation with ethylene in the presence of aluminum chloride so as to ethylate only the benzene and then fractionally dis-

tilling the mixture to produce a fraction reduced in benzene content boiling below about 90° C., a fraction boiling near 136° C. consisting of substantially pure ethyl benzene and a higher boiling fraction consisting of higher ethylated benzenes.

7. The process of obtaining substantially pure cumene from a petroleum oil comprising a substantial amount of benzene and a substantial amount of non-aromatic hydrocarbons wherein the boiling point of the benzene and the non-aromatic hydrocarbons are so close together that they cannot be separated feasibly by a conventional fractional distillation, which process comprises distilling the oils to prepare a fraction boiling below about 90° C. subjecting the fraction to selective propylation with propylene in the presence of aluminum chloride so as to propylate only the benzene and then fractionally distilling the mixture to produce a fraction reduced in benzene content boiling below about 90° C., a fraction boiling near 152° C. consisting of substantially pure cumene and a higher boiling fraction consisting of higher propylated benzenes.

8. A process of obtaining mono alkyl benzenes substantially free of non-aromatic hydrocarbons from a petroleum oil comprising a substantial amount of benzene and a substantial amount of non-aromatic hydrocarbons wherein the boiling points of the benzene and the non-aromatic hydrocarbons are so close together that they cannot be separated feasibly by conventional fractional distillation, which process comprises distilling the oil to prepare a fraction boiling below about 90° C., subjecting the fraction to selective alkylation with a single normally gaseous olefin in a molar ratio of about one-half a mol of olefin to one mol of benzene in the presence of aluminum chloride so as to alkylate only the benzene and then fractionally distilling the mixture to produce a fraction reduced in benzene content boiling below about 90° C. and a fraction boiling above about 90° C. which consists of alkyl benzenes substantially free of non-aromatic hydrocarbons.

9. The process of obtaining substantially pure ethyl benzene from a petroleum oil comprising a substantial amount of benzene and a substantial amount of non-aromatic hydrocarbons wherein the boiling point of the benzene and the non-aromatic hydrocarbons are so close together that they cannot be separated feasibly by a conventional fractional distillation, which process comprises distilling the oils to prepare a fraction boiling below about 90° C. subjecting the fraction to selective ethylation with ethylene in a molar ratio of about one-half a mol of ethylene to one mol of benzene in the presence of aluminum chloride so as to ethylate only the benzene and then fractionally distilling the mixture to produce a fraction reduced in benzene content boiling below about 90° C., a fraction boiling near 136° C. consisting of substantially pure ethyl benzene and a high boiling fraction consisting of higher ethylated benzenes.

10. The process of obtaining substantially pure cumene from a petroleum oil comprising a substantial amount of benzene and a substantial amount of non-aromatic hydrocarbons wherein the boiling point of the benzene and the non-aromatic hydrocarbons are so close together that they cannot be separated feasibly by a conventional fractional distillation, which process comprises distilling the oils to prepare a fraction boiling below about 90° C. subjecting the fraction to selective propylation with propylene in the presence of aluminum chloride so as to propylate only the benzene and then fractionally dis-

selective propylation with propylene in a molar ratio of about one-half a mol of propylene to one mol of benzene in the presence of aluminum chloride so as to propylate only the benzene and then fractionally distilling the mixture to produce a fraction reduced in benzene content boiling below about 90° C. to a fraction boiling near 152° C. consisting of substantially pure cumene and a high boiling fraction consisting of higher propylated benzenes.
